CIGARETTE PACKING MACHINE

Walter Everett Molins, Deptford, London,
EnglandApplication April 12, 1932, Serial No. 604,801, and
in Great Britain April 23, 1931

1 Claim. (Cl. 226—5)

This invention is for improvements in or relating to cigarette packing machines, and refers more particularly to an improved method of feeding cigarettes to a packing machine whereby the cigarettes may be removed from a hopper at a comparatively slow speed of movement without sacrificing the speed and efficiency of the packing machine as a whole.

This object is achieved by simultaneously delivering the cigarettes from a hopper in a number of distinct batches or groups to a conveyor which runs along the bed of the packing machine, and so arranging the speed of movement of the various parts that each set of batches will completely fill, for example, two boxes or packets.

This method of constructing and operating the machine is particularly useful where it is desired to pack cigarettes with their printed inscriptions facing upwards as the mechanism for turning the cigarettes operates with more certainty if it works slowly, but in any case it is desirable to remove cigarettes from the hopper slowly to avoid any shock which may injure the cigarettes and cause tobacco to fall out of the ends.

The invention consists of a packing machine comprising a conveyor adapted to carry a series of packets or other receptacles past a plurality of filling stations where articles are fed into the receptacles, the arrangement of the parts and the relative speed of movement being such that some receptacles receive their charges from some of the filling stations while others receive their charges from other filling stations, the filling apparatus working only at the times when the receptacles are opposite the appropriate filling stations.

The invention will be more particularly described with reference to the accompanying drawings which illustrate the invention as applied to a machine for packing nine cigarettes in packets, and if desired, placing a separating card or picture between the rows which in this case consist of four cigarettes on the bottom row and five on the top.

Fig. 1 is a diagram of the cigarette feeding mechanism and the conveyor arrangement of such a machine.

Figs. 2 to 7 show diagrammatically six stages of the operation of the machine.

Referring to the drawings, the cigarettes are placed in a hopper or box 1 which has four separate outlets beneath which are mounted thin vanes 2, 3, 4, 5 forming slots down which the cigarettes pass to a horizontal table indicated by 6.

A pusher bar 7 carried on an endless chain conveyor 8 removes a single row of cigarettes from each set of vane slots and carries them forward

towards the conveyor 9 of the packing machine. If desired, the cigarettes may first be delivered to a cigarette turning device such as that described in my prior U. S. Patent No. 1,920,707 granted August 1, 1933, from which they are delivered to the packing machine.

Two turning devices are provided in the present instance for the upper rows and indicated by rectangles 10 and 11.

In the present case the packing machine has an intermittently moving conveyor 9 running along the bed of the machine and provided with a series of pockets 12, each of which carries an empty cigarette box.

The first pair of sets of vanes 2 and 3 each deliver four cigarettes to the table and the second pair 4 and 5 each deliver five cigarettes to the table.

Each set of vanes of a pair are spaced apart a distance equal to the pitch of the pockets or carriers 12 on the conveyor 9 of the packing machine, and between the two pairs is a space equal to a double pitch so that when the conveyor stops five boxes will be disposed in the distance covered by the four sets of vanes, the central box being positioned mid-way between the two pairs of sets of vanes.

A card feeding apparatus 13 may be arranged to deliver a card on to the central box in the manner hereinafter described.

The action of the machine will be described in detail with reference to Figs. 2-7, and in these figures the contents of boxes which are complete or will eventually be complete, are illustrated by drawing and the contents of the first three boxes which are discharged from the machine in an incomplete condition are indicated by the references of "C" for card and "5" for five cigarettes. The conveyor pockets are also numbered to render the working clear.

Assuming that all the boxes on the conveyor are empty, and the conveyor is at a standstill with four boxes in line with the four sets of vanes and the central box disposed midway between the sets of vanes, the first movement of the cigarette pusher bar will feed four cigarettes into each box opposite the sets of vanes 2 and 3 which feed four cigarettes, whilst two other boxes opposite vanes 4 and 5 will each receive five cigarettes and simultaneously a card is fed to the central box. These boxes are then as shown in Fig. 2. The conveyor then moves one stage bringing one box containing four in line with the card feed, and the other box containing four in line with the inner set of vanes 3 which feeds

four. At this stage no cigarettes are fed, but only the card, thus producing the result shown in Fig. 3, and then the conveyor moves on one more stage.

5 At the next stop of conveyor 9 two batches of four cigarettes are fed to two fresh boxes and two batches of five to the two leading boxes and a card to the middle box. See Fig. 4.

The conveyor then moves another stage and 10 only a card is fed to the central box, the cigarette feed remaining idle. See Fig. 5. The next movement produces the result shown in Fig. 6 and the next Fig. 7.

It will be seen, therefore, that after the first 15 three boxes have passed beyond the feeding position all the succeeding boxes will be filled with two layers of cigarettes having five cigarettes at the top and four at the bottom, with a separating card in between.

20 The first three boxes which are incompletely filled are discarded, but naturally this only occurs when a machine is being freshly started up after having been completely emptied.

By this arrangement the conveyor of the packing machine may run at the usual speed, thus 25 giving the normal output whilst the cigarettes are fed at half this rate giving the advantages set forth above.

It will be appreciated that the construction 30 described is only given by way of example as numerous arrangements may be worked out for different numbers of cigarettes, using the principle of the invention.

A plunger may, of course, be used for delivering the cigarettes from beneath the vanes without departing from the invention.

In some instances it may be necessary to deliver cigarettes from the various set of vanes 80 alternately to get the required number into the packets.

What I claim as my invention and desire to secure by Letters Patent is:—

In a cigarette packing machine, the combination with means for conveying a plurality of cigarette packets in equidistant spaced relation through a predetermined path, said means operating intermittently to advance the packets step by step through distances equal to the spacing of the packets, of a plurality of cigarette feeding devices disposed adjacent said predetermined path, each of said feeding devices serving to deliver at intervals a batch of cigarettes to one of said packets, said feeding devices being arranged in a plurality of groups, the devices in each group being uniformly spaced, card feeding means disposed intermediate said groups of devices for delivering a card to each packet, means for operating said card feeding device on each advance of the packets, and means for operating the cigarette feeding devices in each group after a number of advances of the packets equal to the number of devices in such group. 95
